Inventor

UNITED STATES PATENT OFFICE

GEORGE BAKER, OF TORRINGTON, CONNECTICUT.

INSULATOR-KNOB.

1,014,934.

Specification of Letters Patent. Patented Jan. 16, 1912.

Application filed August 11, 1910. Serial No. 576,720.

To all whom it may concern:

Be it known that I, GEORGE BAKER, a citizen of the United States, residing at Torrington, in the county of Litchfield and State of Connecticut, have invented a new and useful Improvement in Insulator-Knobs, of which the following is a specification.

This invention relates to certain new and useful improvements in insulating knobs, the object being to provide a knob which is so constructed that the wire to be secured can be easily and quickly arranged within the knob or detached therefrom, thereby overcoming the difficulties now existing in insulators in which a straight groove is used, as it is necessary to match the grooves in order to place the wire therein.

A further object of my invention is to provide an insulator which is formed of two sections normally held together, in such a manner that the knob can be readily secured to its support in order to secure the wire easily and quickly.

A still further object of my invention is to provide a meeting face of the sections with circular grooves, the walls of which are provided with tapering notches adapted to register with one another, and through which wire to be secured is adapted to pass.

Another object of my invention is to provide an insulating knob which is exceedingly simple and cheap in construction, and one in which the securing screw extends through the two sections of the knob centrally for securing the same to a support, and for binding the sections together over a wire.

With these objects in view, the invention consists in the novel features of construction, combination and arrangement of parts, hereinafter fully described and pointed out in the claims.

In the drawing forming a part of this specification: Figure 1 is a side elevation of my improved insulating knob. Fig. 2 is a vertical section through the same. Fig. 3 is a top plan view of the base of the knob. Fig. 4 is an inverted plan view of the top member. Fig. 5 is a detail vertical section of a modified form.

In carrying out my improved invention, I employ a cylindrical knob which is preferably formed of porcelain or any other suitable material, and comprises a base section A, and a top section B which are ar-

ranged one upon the other as clearly shown, 55 and are provided with central bores A' B' through which a screw D is adapted to pass for securing the sections together, and the knobs to a support.

The base A is provided with spurs A² on 60 its bottom, adapted to embed themselves in the support upon which the knob is placed, and the bottom of the base A is provided with a recess A⁴, and the bore A' of the same is enlarged as clearly shown at A² 65 forming a chamber adapted to receive a coiled spring E through which the screw D passes, said spring serving the purpose of holding the screw within the top and bottom member in position to be screwed into 70 the support, and it will be seen that by this construction, the sections of the knob are held in position to be secured to a support, and to receive the wire to be secured.

The top of the base A and the bottom of 75 the top B are provided with circular grooves F, adapted to register with one another when the sections are placed in position, and the outer walls of the grooves are provided with wedge shaped notches F², 80 having semi-circular bottoms F³, the intermediate portions G between the notches forming biting members adapted to engage the wire H when forced between the sections as clearly shown, in such a manner 85 that when the sections are forced together by the screw the wire will be securely locked therein so that all danger of the same moving therein is prevented. The top of the base A is reduced annularly around the central bore, and the bottom of the top B is provided with a central enlargement adapted to fit within the central reduced portion of the base, when the two sections are forced together over the wire so as to prevent the 90 same from moving in respect to each other.

In the modification shown in Fig. 5, I dispense with the recess in the bottom of the base, and carry the enlarged portion of the bore through the base as clearly shown 100 at I, and arrange an additional set of spurs upon the base so as to secure the same without any danger of it turning.

The walls of the grooves F are corrugated or ribbed as shown so as to grip the 105 wire when placed therein to prevent the same from slipping in any way, and it will be seen that by constructing a knob in this

manner a wire can be easily and quickly placed in position or removed therefrom, and when in position will be tightly gripped.

What I claim is:

- 5 1. An insulator formed of two sections secured together by a screw, and means for locking said screw in said sections.
2. An insulator formed of a base, and a top having a screw extending vertically therethrough, and a coiled spring carried by the base through which said screw extends.
- 10 3. An insulator comprising a base provided with a central bore having an enlarged portion, said base being provided with a circular groove in its top having its walls notched, a top mounted on said base provided with a central bore and having its bottom grooved to correspond with the groove of the base, and its walls notched, a screw extending through the vertical bores of said base and top, and a spring mounted in an enlarged portion of said base engaging said screw.
- 15 4. An insulating knob formed of two sections secured together by a screw, the opposing faces of said sections being provided with circular grooves registering with one

another, the outer walls of said grooves being provided with V shaped notches having semi-circular bottoms forming biting members, and a spring carried by said base through which said screw passes, said spring holding said screw within said sections.

5. A device of the class described, comprising a pair of members having current wire receiving seats in adjacent faces thereof, a fastener passed through the said members and adapted to be driven into a support or foundation, and tensioning means carried by the said fastener and acting upon one of the said members for pressing it in clamping relation to the other member.

6. A device of the class described, comprising separable members, a fastener loosely passed through the said members, and spring means acting upon one of the members to retain it in clamping relation to the other member.

GEORGE BAKER.
